DESIGN FOR A DISPLAY STAND

Thomas Carroll Wilson, Piedmont, Calif., assignor to Hills Bros. Coffee, Inc., San Francisco, Calif., a corporation of California

Application September 29, 1941, Serial No. 103,551

Term of patent 3½ years

To all whom it may concern:

Be it known that I, Thomas Carroll Wilson, a citizen of the United States, residing in the city of Piedmont, county of Alameda, State of California, have invented a new, original, and ornamental Design for a Display Stand, of which the following is a specification, reference being had to the accompanying drawing, forming part thereof.

Fig. 1 is a perspective view of the display stand, showing my new design.

Fig. 2 is a front elevational view of the display stand, shown in Fig. 1, on an enlarged scale;

Fig. 3 is a side elevational view; and

Fig. 4 is a top plan view thereof.

I claim:

The ornamental design for a display stand, as shown.

THOMAS CARROLL WILSON.
